Des. 51

John F. Rathbone, Albany, N.Y.
Letters Patent (Design No. 51) dated 10th July 1846

The Schedule referred to in these Letters Patent and making part
of the same.

To all whom it may concern:

Be it known that I, John F. Rathbone of Albany in the County
of Albany and State of New York, have invented a new ornamental de-
sign for a box stove, and I do hereby declare that the following is a full,
clear and exact description of the same, reference being had to the accompany-
ing drawings, making part of this specification, in which Fig. 1 represents
a perspective view of a stove after my design - Fig. 2 exhibits upon a
larger scale the ornamental figures upon the sides and ends which are
respectively similar - The panel a a upon the sides is filled with a com-
position of fruits, flowers, foliage &c. with two crossed cornucopias in
the centre - The figures represented at b b & c c, are continued entirely
around the panels of both sides and ends; forming borders thereto; as
is also the border shown at d d d - The panel e e which is employed
both upon the front and end, is filled by a single cornucopia with
fruit, foliage &c. The borders are the canes for the sides -

2

No. 51

What I claim as my invention and desire to secure by Letters Patent
is the combination of ornamental figures herein shown and described,
forming an ornamental design for a stove.
